UNITED STATES PATENT OFFICE.

MORRIS SCHOENFELD, OF RORSCHACH, SWITZERLAND.

DEVICE FOR HOLDING THE MATERIAL IN EMBROIDERING-MACHINES.

1,008,736.

Specification of Letters Patent. Patented Nov. 14, 1911.

Application filed February 9, 1911. Serial No. 607,458.

To all whom it may concern:

Be it known that I, MORRIS SCHOENFELD, a citizen of the United States, and a resident of Rorschach, in the Canton of St. Gall, Switzerland, have invented certain new and useful Improvements in Devices for Holding the Material in Embroidering-Machines, of which the following is a specification.

In embroidery machines of the large type 10 wherein a movable tambour frame carries the fabric which is to be embroidered, it is common to employ at least two rows of sewing needles arranged in parallel rows and owing to the various mechanisms used on 15 the machine it has been necessary to space the needle rows several feet apart. The tambour frame which is employed to hold the fabric stretched in a vertical plane before the needles and which moves the fabric 20 to give the necessary positions for the stitching, is usually large enough to hold the fabric for both (or more) rows of needles. If only one pair of rollers, horizontally disposed, be mounted on the tambour frame, 25 and the fabric for both (or more) rows of needles be stretched between the one pair of rollers, the fabric will not be stable enough and the needles will tend to press the fabric away, rather than pierce it, the borer will 30 do the same, and in fact the fabric will not be rigid enough to give proper results. In most machines, in fact all the successful machines, two pairs of rollers have been arranged longitudinally upon the tambour 35 frame. The fabric for the top row of needles has been arranged so as to reel from one to the other of the upper pair of rollers; while the fabric for the lower row of needles was arranged to reel from one to the 40 other of the bottom pair of rollers. This reduced the size of the free fabric between any two of the rollers and therefore made the fabric more rigid. The difficulty with this construction however, is, that where the 45 rollers are made for machines up to ten yards in length the weight of the rollers is very great and introduces a difficult problem into the machine, because the tambour frame being a movable part of the machine, moving 50 for every stitch, the shocks thrown upon the supporting frame are very great. Furthermore, the rollers, of the two pairs, which come near the middle of the machine occupy space which could be advantageously used 55 for other parts of the machine; or, if the

rollers were not present, a better view of the embroidery elements could be had. On the other hand when rollers have been arranged in two pairs the amount of fabric which could be rolled upon them has been limited. 60

I have invented a simple arrangement which overcomes the objections to the above constructions, so that only one pair of rollers need be used and my fabric holding device is disposed between the rollers and 65 holds the fabric taut, so that good work can be performed on the fabric, notwithstanding the expanse of material between the two rollers.

By the use of my invention much space 70 is saved at a critical point, the fabric is held better even than when two pairs of rollers are used, and the single fabric can be used for two or more rows of needles. The placing of the fabric is made easier, the weight 75 of two rollers may be eliminated, and because the rollers can be arranged where space is not so important more material may be rolled upon them. Furthermore, the invention makes it possible to place the rollers 80 on the stationary embroidery machine frame, the tambour frame simply carrying the fabric holding means. This will lighten the tambour frame weight and the power necessary to operate it and will reduce the 85 shocks on the machine to a minimum.

All the above objects are obtained by means of a very simple arrangement which is very easily operated, and in the description and drawings I have shown my invention in its best form, intending, however, 90 to cover all structures coming within the spirit of my invention and the scope of my claims.

By pointing out the invention when employed to eliminate one set of rollers I do not wish to limit my invention to this as the same may be used, to at least some advantage, even where two pairs of rollers are used. 95

In the drawings forming a part of this application, Figure 1 is a vertical section through a tambour frame of an embroidery machine, showing one embodiment of my invention, Fig. 2 is a partial elevation 105 thereof, Fig. 3 is a vertical section through a part of the device, Fig. 4 is an elevation of the same, with parts in section, Fig. 5 is a plan view thereof, Fig. 6 is a cross section of a modified form of my invention, 110

and Fig. 7 is a cross section showing a different disposition of the fabric rollers, made possible under my invention.

The tambour frame 1, which may be of ordinary construction and which may be mounted and operated in the usual way, I have shown as comprising horizontal and vertical members, and it carries in its upper part one of the material shafts 2, and in its lower part the other material shaft 3, which are mounted in journals 2^a and 3^a. The material shafts might also be journaled outside of the frame 1 as will appear.

To the middle of the frame members 1^a, is secured an angle iron 4, which lies close to the material 5, stretched between the rollers. On the horizontal arm 4' of the angle iron are placed bars 6 and 7, which extend from the ends of the frame 1 almost to the center thereof. The bars 6 and 7 are adjustably secured to the angle iron by bolts 8, passing through slots in said bars. On the side of the bars 6 and 7 toward the material, pins 10 are mounted, which stand inclined to said bars in a horizontal direction, the pins of the bar 6 extending toward the left while those of the bar 7 extend toward the right. The slots 9 are parallel to the pins 10 so that, when the bars 6 and 7 are moved in the direction of the arrows 11, they are moved in the direction of the pins 10, whereby the latter are moved into the plane of the material and are caused to pierce the same. For moving the bars 6 and 7, levers 12 are pivoted on the angle iron 4, at 12°, each of the upwardly projecting arms of which passes through a slot 13, formed in the angle iron 4 in the direction of its length, and a slot 14, formed in the bars 6 and 7, transversely to the direction of their length. To the downwardly projecting arm of each lever 12 is attached a rod 15, by means of which the bars can be moved. On the opposite side of the material 5 from the angle iron 4, and close to it, is a bar 16, likewise secured to the vertical members of the frame 1. When the material is placed so that the part of it to be embroidered lies between the shafts 2 and 3, the bars 6 and 7 are moved toward the material, by means of the rod 15, whereby the pins 10 pierce the material. The bar 16 prevents the surface of the material from being bent when the pins are inserted. The material is now held firmly and stiffly by the pins, so that the sewing needles can be accurately introduced.

In the modification of Fig. 6, the pins 10 are mounted on a bar 17, secured to an eccentric 19 on a shaft 18. By turning the latter in one or the other direction, the pins are caused to engage or disengage the material.

It is possible, by employing my invention, to relieve the tambour frame of the

weight of the rollers and the fabric they carry, one example of which is clearly shown in Fig. 7. In this embodiment of my invention I have arranged the fabric holding devices, in all respects similar to that shown near the middle of the tambour frame of Fig. 1, and similarly lettered, near the top and bottom of the tambour frame, so that the fabric 5 is firmly held by such devices above and below and other devices of the same kind may be disposed between these two if the expanse of material should require it. The fabric rollers 2 and 3 in this instance are supported upon journal brackets 20 and 22, preferably mounted on the standards 21, which form parts of the main or stationary frame of the embroidering machine. Enough slack 23, is allowed in the fabric between the rollers 2 and 3 to allow for the movements of the tambour frame in relation to the rollers. In this form the tambour frame performs the same functions as in the first construction but my invention permits the mounting of the fabric rollers on the stationary frame instead of the tambour frame. This is important, because the great weight of the rollers and the inactive portions of the fabric is carried upon the stationary frame of the machine and do not have to be moved with the tambour frame. This lightens the construction of the tambour frame and reduces the great shocks of the machine caused by the tambour frame. The tambour frame then has to move only the sheet of fabric upon which the design is being worked. This also has the effect of reducing the necessary counterbalancing weights which counterbalance the tambour frame, so that there is this additional relief to the machine. Furthermore, by reducing the weight of the tambour frame, the force, whether from a pantograph or jacquard, necessary to move the tambour frame, is materially less and I consider this embodiment of my invention a great advance in the art.

It will be apparent that changes may be made in the construction and arrangement of the parts without departing from the spirit of my invention.

Having described my invention, what I claim is;

1. An embroidering machine embodying a tambour frame, and rollers for the fabric, means on said tambour frame for holding the fabric taut for embroidering, comprising bars, arranged to be movable transversely of the plane of the fabric and away from each other, and pins on said bars, arranged to pierce the fabric.

2. An embroidering machine embodying a tambour frame, and rollers for the fabric, means on said tambour frame for holding the fabric taut for embroidering, comprising bars, arranged to be movable trans-

versely of the plane of the fabric and away from each other, and pins on said bars, arranged to pierce the fabric, and means on the side of the fabric opposite the pins, and near the latter, adapted to prevent the fabric from bending when said pins pierce the same.

3. An embroidering machine embodying a tambour frame, and rollers for the fabric, means on said tambour frame for holding the fabric taut for embroidering, comprising movable members, pins carried by said members, and arranged in a substantially horizontal plane, the pins of one movable member diverging as to those of the other, and means whereby said movable members may be moved in the direction of their pins, to cause the latter to pierce the fabric.

4. An embroidering machine embodying a tambour frame, and rollers for the fabric, means on said frame for holding the fabric taut for embroidering, comprising movable members, pins carried by said members, and arranged in a substantially horizontal plane, the pins of one movable member diverging as to those of the other, and means whereby said movable members may be moved in the direction of their pins, to cause the latter to pierce the fabric, and means on the opposite side of the fabric from the pins to prevent the fabric from bending when pierced by the pins.

5. An embroidering machine embodying

a tambour frame, fabric rollers, and means on the tambour frame for holding the fabric taut for embroidering, comprising longitudinally disposed bars having pins arranged in a substantially horizontal plane, the pins of one bar diverging as to those of the other, obliquely to the plane of the fabric, said bars having a slot arranged parallel with their respective pins, a support for the bars having means for engaging in said slots, and means for moving said bars, whereby they will be directed by said slot and engaging member, to cause the pins to pierce the fabric, and means adapted to prevent the pins from bending the fabric.

6. An embroidering machine embodying a stationary frame, fabric rollers mounted on the stationary frame, a movable tambour frame, and means near the top and bottom of the tambour frame for holding the material taut for embroidering, comprising bars arranged substantially parallel with the fabric, pins on said bars, the pins of one bar diverging as to those of the other, and means for moving said bars in the direction of their pins, whereby said pins will be caused to pierce the fabric.

Signed in the city, county and State of New York, this 7th day of February, 1911.

MORRIS SCHOENFELD.
